UNITED STATES PATENT OFFICE.

WILBERT J. EDWARDS, OF FREEPORT, ILLINOIS, ASSIGNOR TO STOVER MANUFACTURING & ENGINE CO., OF FREEPORT, ILLINOIS, A CORPORATION OF ILLINOIS.

HINGE.

Application filed January 24, 1923. Serial No. 614,568.

To all whom it may concern:

Be it known that I, WILBERT J. EDWARDS, a citizen of the United States, residing at Freeport, in the county of Stephenson and State of Illinois, have invented a certain new and useful Improvement in Hinges, of which the following is a specification.

My invention relates to hinges of the type including separable, pivotally connected leaves or sections, and it is my purpose to improve hinges of this kind, whereby one leaf or section may be separated from the pintle that connects it with the other leaf or section, while the pintle is retained by the latter section, so that relative assembly and disassembly of the sections may be accomplished with facility.

My invention also contemplates the employment of a spring to hold the hinge sections in a predetermined normal relative relation, and it is my further purpose to provide for the retention of the spring by the pintle and for the retention of the pintle by the spring when the hinge sections are either assembled or disassembled, so that these parts are at all times positively held in assembly and the possibility of their accidental loss thereby eliminated.

Each leaf or section of my improved includes a pair of lugs and the lugs of the respective sections are adapted to be arranged relatively in overlying relation whereby the pintle aforementioned may be engaged through all of the lugs to pivotally connect the sections. Certain of the lugs are provided with ferrules to form bearings for the pintle, and it is my further purpose to so form these lugs that the ferrules and the bearings formed thereby are concealed when the hinge sections are assembled, to the end that the hinge is rendered attractive in appearance, protuberances that might catch and tear a person's clothing are avoided, and the strength and durability of the hinge considerably enhanced.

My inventive idea is capable of embodiment in different mechanical structures, certain of which are shown in the accompanying drawings, but it is to be understood that the structures illustrated are intended merely as disclosures of the essential features and novel characteristics of my invention in preferred forms, and that its scope is as defined in the appended claims.

In the drawings, wherein like characters

of reference denote corresponding parts in related views—

Figure 1 is a front elevation of a hinge embodying the novel and essential characteristics of my invention;

Figure 2, a view similar to Figure 1, partly in section, showing the hinge sections separated;

Figure 3, an end view of the hinge as it is shown in Figure 1;

Figure 4, a transverse section on the line 4—4 of Figure 1;

Figure 5, an end view of the hinge showing the sections separated as in Figure 2;

Figure 6, a section on the line 6—6 of Figure 1;

Figure 7, a section on the line 7—7 of Figure 2;

Figure 8, a view similar to Figure 1 showing a slightly modified form of hinge;

Figure 9, a view similar to Figure 8, partly in section, showing the hinge sections of the modified form of hinge separated;

Figure 10, a section on the line 10—10 of Figure 8; and

Figure 11, a section on the line 11—11 of Figure 9.

Referring now to the drawings in detail, particularly to Figures 1 to 7 inclusive, it will be observed that my improved hinge consists essentially of a pair of leaves or sections 10 and 11, a pintle 12 engaged through said sections to pivotally connect them, and a coil spring 13 surrounding the pintle and acting to hold the sections in a predetermined relative relation.

Each hinge section is provided with a pair of relatively spaced, laterally extending, alined lugs, through which the pintle 12 is engaged, whereby the sections are pivotally connected, section 10 having the lugs 14 and 15 and section 11 having the lugs 16 and 17 as shown. The lugs of section 11 are disposed slightly closer together than the lugs of section 10, so that in the assembled relation of the sections, the lugs 16 and 17 fit between and respectively against the lugs 14 and 15, so that any substantial amount of play between the sections is prevented.

An aperture is formed in each of the lugs 14, 15, 16 and 17 to receive the pintle 12, and as shown, each lug is provided with a ferrule 18 surrounding its aperture to form a relatively extensive bearing for said pintle. The ferrule on both lugs 14 and 15 of section

10 face inwardly; that is, they extend from adjacent sides of the lugs 14 and 15, while, with respect to section 11, only the ferrule on lug 17 faces inwardly and the other ferrule, the one on lug 16, faces outwardly. Each of the lugs, with the exception of lug 17, is dished reversely with respect to the direction of extent of its ferrule, whereby the latter is disposed entirely within the 10 plane of that side of the lug from which it extends. This not only results in the ferrules being concealed, whereby the hinge is rendered attractive in appearance, but the strength and durability of the lugs is enhanced and protuberances that might catch in and tear a person's clothing are avoided.

One end of the pintle 12 is provided with a head 19 that forms a stop engageable with the lug 14 to limit insertion of the pintle 20 through the lugs, and the other end of the pintle normally projects outwardly beyond the lug 15 and preferably is tapered or rounded, as shown clearly in Figure 1 of the drawings to facilitate its insertion in and 25 removal from the lugs. Near its head 19 said pintle is reduced in diameter throughout a portion of its length as indicated at 20, said reduced portion flaring outwardly towards the head 19 as at 21, while remotely 30 from the head 19 said reduced portion terminates in a shoulder 22. Near its free or rounded end, said pintle also is slightly reduced as indicated at 23, so that when the pintle is engaged through the lugs of the assembled sections and moved slightly laterally, the shoulders formed by this reduced portion 23 will engage the lugs 15 and 17 and consequently prevent accidental removal of the pintle.

40 The coil spring 13 surrounds the pintle 12 between the lugs 16 and 17 of section 11, and at one end bears against said section 11, and at its other end against the section 10, whereby it acts torsionally to hold the sections in 45 a predetermined relative relation. Due to the engagement of the ends of this spring with the respective hinge sections, a lateral thrust is exerted against the pintle when the latter is fully engaged in the sections to hold 50 its reduced portion 23 eccentric with respect to the apertures in the lugs 15 and 17 whereby the shoulders formed by said reduced portion function as shown in Figure 6 to prevent accidental withdrawal of the pintle 55 as aforementioned. However, upon predetermined pressure being exerted against the end of the pintle that normally projects beyond the lug 15, the retaining shoulder formed by the reduced portion 23 will disengage from the lug 15 and the pintle will become axially alined with the apertures in the lugs, whereby it may be moved longitudinally to the position shown in Figures 2 and 7, in which position, its reduced portion 20 60 is disposed in alinement with the lugs 14

and 16 and its free end flush with or inwardly of the inner face of the lug 15, as shown, whereupon the sections may be relatively separated and the section 10 separated from the pintle by relative lateral movement 70 of these parts that is permitted by a run-out slot 25 in the lug 14 through which the reduced portion 20 of the pintle may pass. In this connection it is to be observed that a run-out slot similar to the one in lug 14 may 75 be formed in the lug 15, so that the hinge sections may be reversed in assembling them whereby the necessity of care in assembly may be avoided. However, the provision of a slot 25 in the lug 15 obviously is unnecessary and its provision is optional.

From the foregoing it is apparent that the sections 10 and 11 are separable from each other and that the section 10 is separable from the pintle when the pintle is engaged 85 through both lugs of section 11. Accordingly, disassembly of the hinge may be accomplished with facility, and inasmuch as the spring exerts a lateral thrust against the pintle in the partial withdrawn position of the same illustrated in Figures 2 and 7, the shoulder 22 engages with the lug 16 as shown in the latter figure, to hold the pintle against accidental loss from such partially withdrawn position. On the other hand, by manipulating the pintle to aline its body portion with the aperture in the lug 16, it may be fully withdrawn to allow removal of the spring. The spring at one end surrounds the ferrule 18 on the inner 90 face of the lug 17, whereby its assembly with the section 11 normally is maintained while the pintle is being partly withdrawn. On complete withdrawal of the pintle, however, the spring leaves ferrule 17 and comes 105 out with the pintle. In other words, the spring is never retained in either hinge section when the pintle is wholly withdrawn. Again, in partial withdrawn position of the pintle, that is, when the pintle is engaged 110 through both lugs of the section 11, it is impossible to remove the spring, because of the pintle, and consequently, the pintle acts to retain the spring assembled with respect to the section 11 and, reversely, the spring, 115 by exerting a lateral thrust on the pintle, acts to retain the pintle in assembly with the section 11 whether this section is or is not assembled with respect to section 10. Tapering of the pintle at 21 and at its free 120 end serves to guide the same into the apertures in the lugs when assembling the sections, so that it is only necessary, after the respective lugs are relatively alined, to exert pressure on the head of the pintle to 125 secure permanent assembly of the parts of the hinge.

It is desirable to prevent rotation of the pintle with respect to the section 10, and to this end I form on the pintle a boss 130

26 that is engageable in the run-out slot
25 when the pintle is fully engaged with the
sections.

In Figures 8 to 11 inclusive I have illus-
5 trated a slight modification which consists
in forming each lug 14' and 15' of section
10' with a run-out slot 25', and in forming
the free end of the pintle 12' with a reduced
extension 27. By this arrangement, the
10 necessity of moving the free end of the pin-
tple to a flush position or inwardly with
respect to the inner face of lug 15' to ef-
fect disassembly is avoided, since the re-
duced extension 27 may project outwardly
15 beyond the lug 15' and still be capable of
lateral movement through the run-out slot
25' in said lug. In all other respects, the
construction illustrated in Figures 8 to 11
is the same as in Figures 1 to 7.

20 I claim:—

1. A hinge comprising a pair of sections,
a pintle pivotally connecting said sections,
and means whereby the sections may be sepa-
25 rated in different relative positions thereof
while the pintle is engaged through both
sections.

2. A hinge comprising a pair of sections,
a pintle pivotally connecting said sections,
and means whereby the sections may be
30 separated laterally in different angular po-
sitions of the sections with respect to each
other while the pintle is engaged through
both sections.

3. A hinge comprising a pair of sections,
35 a pintle engaged through said sections to
pivotally connect them, and means rendered
effective in any angular relative relation of
the sections by movement of the pintle to a
predetermined position with respect to
40 one of the sections while engaged through
both sections to permit separation of the
sections.

4. A hinge comprising a pair of sections,
45 a pintle engaged through said sections to
pivotally connect them, and means rendered
effective by movement of the pintle to a pre-
determined position with respect to one of
the sections while engaged through both
50 sections to permit separation of the sections,
and means effective in all other positions
of the pintle with respect to said section
while the latter is engaged through both
sections to deny separation of the sections.

5. In a hinge, a hinge section and a pintle,
55 means operable in one position of said pintle
while engaged through said section to per-
mit separation of the pintle from the sec-
tion, and means operable in all other posi-
tions of the pintle with respect to said sec-
60 tion while engaged therethrough to deny
separation of the pintle from the section.

6. A hinge comprising a pair of sections
each having a pair of apertured lugs, one
lug of one section being provided with a
65 slot extending from the edge of the lug

into its aperture, and a pintle engaged
through both lugs of each section to pivot-
ally connect the sections, said pintle having
a reduced portion for removal through said
slot in a predetermined position of the pin-
70 tle whereby one section may be separated
from the pintle when the latter is engaged
through the lugs of the other section.

7. A hinge comprising a pair of sections
each having a pair of apertured lugs, one
lug of one section being provided with a
slot extending from the edge of the lug
into its aperture, a pintle engaged through
75 both lugs of each section to pivotally con-
nect the sections, said pintle having a re-
duced portion for removal through said
slot in a predetermined position of the pin-
tple whereby one section may be separated
80 from the pintle when the latter is engaged
through the lugs of the other section, and
a boss on said pintle normally engaged with
said slot whereby rotation of the pintle with
respect to one section is prevented.

8. A hinge comprising a pair of sections
each having a pair of apertured lugs, a
pintle engaged through said lugs to pivot-
ally connect the sections, and ferrules ex-
tending respectively from certain of said
85 lugs to provide bearings for said pintle, the
material of said lugs being dished reversely
with respect to the direction of extent of
said ferrules whereby the latter are dis-
posed entirely within the plane of that side
of the lugs from which they extend.

9. A hinge comprising a pair of sections
each having a pair of lugs, the lugs of one
section being adapted to fit between the
lugs of the other section, a pintle engaged
through said lugs to pivotally connect the
90 sections, the outwardly disposed lugs being
dished outwardly and one of the inwardly
disposed lugs being dished inwardly, and
a ferrule extending from each dished lug
to provide a bearing for said pintle, said
95 ferrules being disposed, respectively, within
the dished portions of the lugs from which
they extend whereby they are normally con-
cealed.

10. A hinge comprising a pair of sections,
a spring between said sections acting to re-
sist movement of one section in a predeter-
mined direction with respect to the other
section, a pintle engaged through said sec-
tions and said spring and pivotally con-
100 necting the sections, and means whereby
the sections may be separated in different
angular positions of the sections with re-
spect to each other while the pintle is en-
gaged through both sections and through
105 said spring.

11. A hinge comprising a pair of sections,
a pintle engaged through said sections to
pivotally connect them, a spring surround-
ing the pintle and bearing torsionally at
one end against one section and at its other
110

end against the other section, and means whereby the sections may be separated in different angular positions of the sections with respect to each other while the pintle is engaged through both sections and through the spring.

12. A hinge comprising a pair of sections each having a pair of apertured lugs, a pintle engaged through said lugs to pivotally connect the sections, and a torsion spring surrounding said pintle and bearing at its ends against the sections to hold the same in a predetermined relative position, said spring exerting a lateral thrust against said pintle, and a reduced portion on the pintle providing a shoulder engageable with an edge of one of said lugs under the influence of the aforesaid lateral thrust of the spring,

thereby to hold the pintle normally engaged through said lugs. 20

13. A hinge comprising a pair of sections, each having a pair of lugs provided with apertures, each lug of one section having a run-out slot leading from its aperture, and a pintle engageable through said lugs to 25 pivotally connect the sections, said pintle having a pair of reduced portions for removal through said run-out slots in a predetermined position of the pintle, whereby one of said sections may be separated from the pintle when the latter is engaged through the lugs of the other section. 30

In witness whereof, I have hereunto subscribed my name.

W. J. EDWARDS.
